UNITED STATES PATENT OFFICE.

JOSEPH BAGNALL, OF NORTH ATTLEBORO, MASSACHUSETTS.

BRACELET.

No. 808,805.

Specification of Letters Patent.

Patented Jan. 2, 1906.

Application filed May 13, 1905. Serial No. 260,846.

To all whom it may concern:

Be it known that I, JOSEPH BAGNALL, a citizen of the United States, residing at North Attleboro, in the county of Bristol and Commonwealth of Massachusetts, have invented certain new and useful Improvements in Bracelets, of which the following is a specification.

This invention relates to bracelets, collars, and like articles, and more particularly to the hinging of these articles in such a manner as to afford the easy application of the same to the wearer.

The invention relates more particularly to that style of bracelet which is usually made of round or tubular stock and in which the feature of simplicity and neatness is a very important factor.

It is the object of the present invention to render a hinged bracelet of this type self-closing and at the same time to provide working parts of such a nature as to preserve the external simplicity and neatness which the type demands. To this end, therefore, I have provided a certain arrangement of parts whereby a spring, moving plug, and a hinge shall be made to coact to produce the desired results and yet be so contained in and related to the rest of the article as to preserve the effect desired, as above mentioned. The particular form and structure of these parts will be more fully described in the specification which follows and shown in the drawings, which form a part thereof, and in which—

Figure 1 shows a view of a closed bracelet containing the invention; Fig. 2, a view of the same open; Fig. 3, an edge view of the bracelet; Fig. 4, a partial section of Fig. 1, showing the hinge; Fig. 5, the same section in Fig. 2.

1 and 2 are the two sections of a bracelet of the class described, having a hinge-block 3 soldered into section 2 and pivoted at 4 in section 1. The block 3 has on its pivoted end a bevel 5, which faces inwardly, so that the longer edge of the hinge-block is on the outside of the bracelet and the corner thereof forms the point 13.

6 is a plug contained within the section 1 and curved to conform to the curve of said section. It has its end adjacent to the beveled face 5 of the hinge-block 3 rounded, as at 6^a, to afford an easy bearing for the parts in their movements. The plug is made of sufficient length to prevent its rocking when the

hinge is bent, and on account of its curve in the tubular section it is prevented from rolling, and the rounded end is thus presented always as an even bearing for the end of the hinge. 7 is a coil-spring between said block and the nipple 8, which is soldered into the end of the section 1 to engage the end of section 2 and at the same time to afford a backing for the spring 7. By employing this nipple as a backing no pin is necessary across the tube, and the exterior is thus unmarred. By using a long plug I am able to reduce the length of the spring, thus making a saving in spring-stock and giving a more even resiliency.

9 is a cup soldered into the end of section 2 to receive the nipple 8 and give the bracelet a finished appearance.

The operation of the parts is as follows: In opening the hinged members the end of the hinge 3 presses against the block 6 and pushes it back, compressing the spring until its point 13 passes the center of the plug, at which point the plug begins to return and assists in holding the bracelet open. In closing the bracelet as soon as the point of the hinge has been brought by the center of the plug it receives pressure from the spring, which tends to throw it into the closed position. The nipple 8 and cup 9 merely act to aline the ends of the bracelet and prevent the lateral racking of the joint.

What I therefore claim, and desire to secure by Letters Patent, is—

1. In an article of the class described, a pair of curved sections, one of which is tubular, a hinge portion beveled on its inner side on the other of said sections and pivoted with its beveled end within said tubular section, a block in said tubular section having a rounded end, and a spring for holding said block with said rounded end in contact with said beveled end.

2. In an article of the class described, a pair of curved tubular sections, a hinge-block attached to one section and pivoted within the other section, said block being beveled inward on its end, a curved block within the other of said sections having a rounded end adjacent to and in the line of the end of said hinge, and a spring behind said block for pressing it against said hinge for closing and maintaining closed said hinged section.

3. In an article of the class described, a pair of curved sections, tubular throughout, a hinge-block attached to the end of one sec-

tion and pivoted within the other section, the end of said block being beveled inwardly, a bent block in said other section having a curved end adjacent to and in the line of said 5 hinged block, a stop in said last-named tubular section and a spring between said stop and block for pressing said block against said hinge to close and maintain closed said hinged section.

- 10 4. In an article of the class described, a pair of curved sections, one of said sections being tubular, a hinge-block attached to one section and pivoted within the other section, said block being beveled inward on its end, a 15 curved block within the other of said sections having a rounded end adjacent to the end of said hinge-block, and a spring behind said curved block for pressing it against said hinge-block for closing and maintaining closed 20 said hinged section.

5. In an article of the class described, a pair of curved sections, one of said sections being tubular throughout, a hinge-block attached to the end of one section and pivoted within the other section, the end of said block being beveled inwardly, a bent block in said other section having a curved end adjacent to said hinge-block, a stop in said last-named tubular section and a spiral spring between 25 said stop and curved block for pressing said 30 curved block against said hinge-block to close and maintain closed said hinged section.

In testimony whereof I affix my signature in presence of two witnesses.

JOSEPH BAGNALL.
